UNITED STATES PATENT OFFICE.

WILLIAM F. MOORE, OF PLAINFIELD, NEW JERSEY.

CONTAINER.

988,804.

Specification of Letters Patent.

Patented Apr. 4, 1911.

Application filed July 8, 1910. Serial No. 571,050.

To all whom it may concern:

Be it known that I, WILLIAM F. MOORE, a citizen of the United States of America, and residing at Plainfield, in the county of 5 Union and State of New Jersey, have invented a certain new and useful Improvement in Containers, of which the following is a specification.

My invention relates to containers and 10 particularly to partitioned containers, the object of my invention being to provide a cheaply manufactured partitioned receptacle of sheet metal, to contain for example in one chamber shaving powder, and in another 15 chamber talcum powder, a suitable closure being provided to simultaneously close the outlet from both chambers, while permitting either to be opened separately.

The article is intended particularly for 20 travelers and domestic use, and being cheaply made is intended for but a single use so that it may be thrown away after its contents are exhausted.

In the accompanying drawings, Figure 1 25 is a perspective view of a container for toilet preparations in which my invention is embodied in one form; Fig. 2 is a cross section of the head thereof; Fig. 3 is a plan of the container partially broken away; 30 Fig. 4 is a horizontal cross section of the body portion of the container in one form; Fig. 5 is a similar view of the same with the partition integral with the side walls; Fig. 6 is a broken enlargement of the same showing the method of making the joints; and 35 Fig. 7 is a broken perspective of the partition made in one piece.

In the form illustrated my improved container comprises a body A and a head B independently formed out of sheet metal, but 40 assembled and permanently united in the finished article by soldering or sweating the same together in well known manner. The body portion A is subdivided into two chambers 45 10 and 11 by a partition a (Fig. 4) which may be stamped out independently as illustrated and provided with grooved edges which slide on ribs 12 formed on the inner face of the body A. If preferred, the 50 partition may be stamped out as part of the blank from which the body of the box is formed, and angled to its transverse position as shown at a' in Fig. 5. One end of the blank is at 13, the other end at 14, the 55 offsets 15 and 16 pressed out of the intermediate portion of the metal, forming rabbets

with which the offset edges of the metal interlock and form good joints for soldering or sweating together. The head B is secured to the body A by the skirt b which fits 60 closely over the upper edge of the body A and is soldered or sweated on after the powders have been placed in the compartments 10 and 11. A partition b' which corresponds with the partition a or a' in the 65 body, is provided and its lower edge shaped to engage the latter in any suitable way to form a tight joint therewith. In Fig. 2 the lower edge 17 of the partition is offset or beveled for this purpose. The partition 70 for the body may be shaped to extend into the head however, as shown for example in a', Fig. 7, a rib, corresponding to rib 12 in the body, being pressed into the head (Fig. 1).

On each side of the partition in the head B I provide outlet apertures 18 and 19 opening into the chambers 10 and 11 respectively. In the form shown the aperture 18 is a single large hole through which shaving powder 80 may be conveniently discharged into the center of the shaving brush, while the aperture 19 comprises a group of small holes through which talcum powder is dispersed.

In order to normally close both apertures 85 and thus render the container suitable for transportation without loss of its contents, I provide a closure comprising a curved plate 20 with lugs 21 by which it is pivotally mounted on the head. Stops 22 may be 90 struck up from the curved outlet face of the head to work in the slots 23 and thus limit the extent of the oscillation of the plate 20. The curvature of the plate and of the outlet 95 face of the head being the same and the pivots 24 being located at the center of curvature of said plate, the latter is maintained in close contact with the outlet face of the head and thus serves as an efficient closure for the ports 18 and 19. If it is desired to open 18, the plate is pushed over to clear the same, its movement being limited by the stop 22 so that the port 19 is not also uncovered; and vice versa. It is advisable to make the plate fit quite close to the outlet 100 face of the head to insure a tight closure, and the edges 25 of the slide are preferably milled the better to enable a user to overcome the resulting friction in shifting the slide from one position to another. The 110 friction between the plate and the head is sufficient to hold the plate in a position mid-

way between the two extreme positions. When in such middle position, the discharge openings of both compartments are closed.

Obviously the construction illustrated 5 may be variously modified without departing from my invention and I do not limit myself to the details shown or the use of particular contents.

I claim as my invention:

10 A container comprising a body portion with a head portion secured thereto, a partition dividing said container into independent chambers, said head portion being provided with a curved top through which

opens an independent port from each chamber of the container, in combination with a rocking closure for said ports pivoted on said head, said closure having the curvature of said outlet face and being adapted to close said ports simultaneously or to open 20 one alone, substantially as described.

In testimony whereof I have signed my name to this specification, in the presence of two subscribing witnesses.

WILLIAM F. MOORE.
